(57) **CLAIM**

The ornamental design for a multifunctional power supply assembly as shown and described.

DESCRIPTION

FIG. 1 is a front, right and top perspective view of a multifunctional power supply assembly, showing my design in a connected configuration.

FIG. 2 is a front, right and top perspective view of a multifunctional power supply body of the multifunctional power supply assembly shown separately to show aspects of the design not visible when in a connected configuration.

FIG. 3 is a rear, left and bottom perspective view of FIG. 2.

FIG. 4 is a front elevation view of FIG. 2.

FIG. 5 is a rear elevation view of FIG. 2.

FIG. 6 is a left side elevation view of FIG. 2.

FIG. 7 is a right side elevation view of FIG. 2.

FIG. 8 is a top plan view of FIG. 2.

FIG. 9 is a bottom plan view of FIG. 2.

FIG. 10 is a front, right and top perspective view of a multifunctional power supply base of the multifunctional power supply assembly shown separately to show aspects of the design not visible when in a connected configuration.

FIG. 11 is a rear, left and bottom perspective view of FIG. 10.

FIG. 12 is a front elevation view of FIG. 10.

FIG. 13 is a rear elevation view of FIG. 10.

FIG. 14 is a left side elevation view of FIG. 10.

FIG. 15 is a right side elevation view of FIG. 10.

FIG. 16 is a top plan elevation view of FIG. 10; and, FIG. 17 is a bottom plan elevation view of FIG. 10.

The broken lines shown in the drawings are included for the purpose of illustrating portions of the multifunctional power supply assembly that form no part of the claimed design.
